Attorney

UNITED STATES PATENT OFFICE.

GOVERNOR L. BREWER, OF KENT CITY, MICHIGAN.

SPARK-PLUG.

1,321,710.

Specification of Letters Patent. Patented Nov. 11, 1919.

Application filed April 8, 1919. Serial No. 288,620.

To all whom it may concern:

Be it known that I, GOVERNOR L. BREWER, a citizen of the United States, residing at Kent City, in the county of Kent and State of Michigan, have invented certain new and useful Improvements in Spark-Plugs, of which the following is a specification.

This invention relates to spark-plugs for use in connection with internal combustion engines and other purposes; and it consists in the novel construction and combination of the parts hereinafter fully described and claimed.

In the drawings, Figure 1 is a side view of the spark plug. Fig. 2 is a vertical section through the spark plug; and Fig. 3 is a plan view of the same, from below.

The spark plug has a tubular supporting base 2 provided with a screwthreaded portion 3 for connecting it to the cylinder of the engine or other object to which it is to be attached. The upper part of the base has a chamber 4 connected to the tubular base by an inclined shoulder 5, and having 25 an internally screwthreaded portion at its upper end.

A tubular sleeve 6 is provided and has a screwthreaded lower end portion 7 which is screwed into the upper part of the base. 30 The upper end portion of this sleeve is tapered externally so that its top edge is very thin. The bottom end 8 of the sleeve is beveled or inclined in the reverse direction to the shoulder 5 on the base.

35 A main plug 10 of insulating material is arranged in the base and sleeve, and it has an enlargement or collar 12 which is arranged in the chamber 4 between the end of the sleeve and the shoulder on the base.

40 Washers 14 and 15 are interposed between the collar 12 and the sleeve and the shoulder respectively, and the upper washer has a downwardly projecting flange 16 which overlaps the cylindrical part of the collar.

45 The upper end portion 17 of the plug is cylindrical, and it has a cylindrical cover or shield 18 of asbestos interposed between it and the lower tubular part of the sleeve. The upper end portion of the plug has a shoulder 19 and a projection 20.

50 The lower electrode member 21 is secured centrally in the plug 10 with its ends projecting therefrom. A bar electrode 24 is secured to the bottom end of the base, and is 55 connected to one pole of any approved bat-

tery or source of electricity. This bar electrode extends crosswise under the end of the lower electrode member 21, and its middle part is curved upwardly so as to form an ignition spark gap with the end of the lower 60 electrode member 21. The spark is fan-shaped and is localized at the middle part of the crossbar by this construction.

An upper plug 26 of insulating material is provided, and has a circumferential 65 groove 27 at its middle part. The plug 26 is inserted in the upper end portion of the sleeve 6, and the top portion of the sleeve is crimped or bent into engagement with the groove 27 so as to hold the plug 26 in place. 70

The upper plug 26 has a shoulder 28 at its lower end and a projection 29. A short sight tube 30 of glass or other transparent material is inserted in the sleeve between the two plugs before the upper plug is secured in place, and is held in place between the shoulders 19 and 28. The projections 20 and 29 project a little into the end portions of this sight tube. By crimping or bending the thin upper end of the sleeve 75 the glass sight tube can be secured in position without breaking it. Sight tubes are easily broken when secured between screw-threaded portions.

An upper electrode member 32 is screwed 80 or is otherwise secured into the upper plug 26 so as to be adjustable longitudinally in it, and its lower end forms a spark gap with the upper end of the lower electrode member 21. Sight openings 33 are formed on opposite sides of the sleeve opposite this spark gap so that the working of the device may be visible. The upper end portion of the electrode member 32 projects from the upper plug 26, and is provided with a lock nut 90 34 and a clamping nut 35 for the wire 36 which conducts the electricity to the upper electrode. The other electric wire is connected with the base of the plug in the usual way to form a circuit through the device. 95 100

The washers 14 and 15 are preferably made of asbestos, or are lined with asbestos. They make gas tight joints against the pressure in the lower cylinder, and prevent the main plug from getting chipped and broken. 105 The asbestos cylinder 18 also preserves the part 17 from injury from vibration which is a frequent cause of fracture.

What I claim is:

In a spark plug, a base portion, a sleeve 110

secured thereto, a cylindrical liner of asbestos in the lower part of the sleeve, a main plug of insulating material secured between the base and sleeve with its upper end projecting through the said liner, an upper plug of insulating material secured in the upper

end of the sleeve, and electrodes carried by the two said plugs and forming an auxiliary spark gap.

In testimony whereof I have affixed my ¹⁰ signature.

GOVERNOR L. BREWER.
